UNITED STATES PATENT OFFICE

2,039,536

COMPOSITION BUILDING ELEMENT

Warner D. Johnson, St. Louis Park, Minn.

Application October 2, 1931, Serial No. 566,559

6 Claims. (Cl. 154—45.9)

This invention relates to composition building elements for interior and exterior construction and has for the primary object, the provision of a device which will provide efficient insulation against weather elements and a resistance against fire and protection from vermin and germs and a deadener of sound.

Another object of this invention is the provision of chemically treated bodies or slabs which will possess insulating qualities and be capable of withstanding various kinds of strains or stresses and so constructed as to have interfitting connections with each other when assembled.

A further object of this invention is the provision of facings for the slabs to provide attractive and artistic appearance thereto and a novel method of securing the facings and slabs together to provide them of substantial integral construction to render them capable of withstanding severe wear and to meet all building requirements and which may be manufactured and sold at a comparatively low cost.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a perspective view illustrating a brick employed as a facing element in one form of my invention.

Figure 2 is a perspective view illustrating the composition body or slab.

Figure 3 is a plan view illustrating the bricks in a mold or rack.

Figure 4 is a sectional view taken on the line 4—4 and showing clearly the bonding element applied to the facing elements or bricks.

Figure 5 is a sectional view illustrating the slab applied to the facing elements or bricks and ready to be positioned in a press.

Figure 6 is a side elevation illustrating the interlocking connections between the slabs and bodies.

Figure 7 is a bottom plan view illustrating the same.

Figure 8 is a sectional view taken on the line 8—8 of Figure 6.

Figure 9 is a plan view illustrating a modified form of brick or facing element having attaching lugs.

Figure 10 is a sectional view illustrating the modified form of facing elements or bricks asso-

ciated with a modified form of slab and located in the mold or rack.

Figure 11 is a similar view showing the modification when completed or removed from the mold or rack. 5

Figure 12 is a sectional view illustrating a modified form of building element in which the facing elements represent bricks and the latter recessed to receive lugs.

Figure 13 is a perspective view illustrating a modified form of building element in which the facing elements represent shingles. 10

Figure 14 is an end elevation illustrating the same.

Figure 15 is a perspective view illustrating the facing elements shown in Figure 13 prior to being secured to the slab. 15

Figure 16 is a plan view illustrating a modified form of my invention in which the facing elements consist of tile shingles. 20

Figure 17 is an end elevation illustrating the same.

Figure 18 is a sectional view illustrating means of connecting the roofing or tile shingles to the slab. 25

Figure 19 is a plan view illustrating the convex shingles or tilings.

Figure 20 is an end elevation illustrating the same.

Figure 21 is a view similar to Figure 19 showing the concave shingles or tilings. 30

Figure 22 is an end elevation illustrating the same.

Figure 23 is a fragmentary sectional view, illustrating a modified form of means of securing the tile shingles to the body or slab. 35

Figure 24 is a perspective view illustrating a modified form of my invention in which the facing element represents clapboarding.

Figure 25 is an end elevation illustrating the same. 40

Figure 26 is a perspective view illustrating the clapboard facing prior to being secured to the slab.

Figure 27 is a perspective view illustrating a facing element representing tiling for interior construction. 45

Figure 28 is an end elevation illustrating the same.

Figure 29 is a perspective view illustrating the facing element shown in Figure 27 after being applied to the slab. 50

Figure 30 is a perspective view illustrating a facing element for interior wall or ceiling construction. 55

Figure 31 is an end elevation illustrating the same.

Referring in detail to the drawings, the numeral 1 indicates a slab or body constructed from long, tough, fibrous material, such as wood fibre, grass, weeds, and other similar materials. The selected material is preferably seasoned and chemically treated to resist fire and pressed into a solid mass to provide the slab or body 1. One face of the slab or body is coated with a solution of magnesium chloride and then covered with a coat of thin cement having the consistency of cream. The slab or body is capable of resisting fire, and insulation against heat or cold and dampness and will be non-conductive of noises and non-penetrative by vermin and disease germs. The slab or body may be of varying dimensions, preferably of a thickness ranging from one half inch to one inch while the other dimensions thereof may remain standard which is conventional in building construction.

A facing 2 is provided with the slab or body 1 and is in the form of individual bricks 3. The bricks 3 are of a conventional dimension except for their thickness as shown in Figure 1. The thickness being much less than an ordinary brick.

A frame 4 of substantially the size of the slab or body is divided by a series of partitions 5 and 6. The partitions being so arranged that when they receive the bricks, the latter will resemble a brick wall of ordinary formation. The frame 4 rests upon a plate 7 to retain the bricks within the frame and project slightly beyond one face 35 of said frame and are coated with a solution of magnesium chloride over which is placed a coating of thin cement having a creamy consistency. The slab or body 1 is then applied to the bricks as shown in Figure 5 with the treated face thereof next to the treated faces of the bricks. The slab or body resting upon the bricks within the frame 4 is then placed in a hydraulic press and subjected to a desired pressure causing the cement to be forced deep into the voids of both 45 the body or slab and the bricks causing said parts to become substantially of integral construction.

The body or slab has its side edges cut away to provide flanges 8 which flanges of slabs or bodies 50 when assembled in wall formation will have overlapping relation. The ends of the slab or body are cut away to provide spaced tenons 9 and notches 10. The walls of the notches and edges of the tenons are bevelled so that when 55 slabs or bodies are assembled in wall formation the tenons will fit within the notches establishing interlocking connections between said bodies or slabs. Due to the connections of the slabs or bodies with each other when in wall formation 60 waterproof or leakproof connection is established therebetween and the assembled wall from its outer face will have the appearance of an ordinary brick wall.

Anchoring plates 11 are suitably fastened to 65 the studding of the wall construction and have struck out therefrom a series of tines 12 which may be driven into the slabs or bodies thus effectively anchoring the latter to the studding of the wall construction.

Referring to my modified form of invention 70 as shown in Figures 9 to 11 inclusive, the bricks constituting the facing have formed thereon tapered or substantially conical shaped lugs 13 received within cylindrical pockets 14 formed

within the slab or body and when the slab or body and the bricks are subjected to pressure, the material of the slab or body will close in and about the lugs 13 thereby firmly anchoring the face bricks to the slab or body as shown in Figure 11.

Referring to Figure 12 the bricks are provided with recesses 13' so that when the slab or body is applied, the material thereof will enter the recesses forming lugs 14' or bonds therebetween.

Referring to Figures 13 to 15 inclusive, a modified form of my invention is disclosed and which consists of a facing 15 secured to a slab or body 16 similar in construction to the slab or body 1 by the method heretofore set forth. The facing 15 is constructed from cement or similar material and has its outer face grooved and lined, as shown at 17 and 18 to represent shingles so that the device may be employed in wall or roofing construction wherein it is desired that the device have a shingled appearance.

Referring to Figures 16 to 22 inclusive, a modified form of my invention is disclosed in which a facing 19 has the appearance and the advantages of tile roofing and the body or slab 20 is 25 similar in construction with the slab or body 1 and is provided with cylindrical pockets for receiving tapered lugs 21 formed integral with fillers 22, each formed integral with a tile shingle 23. When the facing 19 representing the tile roofing 30 is assembled on the body or slab 20 by the method disclosed by Figures 9 to 11 and heretofore described, the tile shingles will have overlapping relation, forming ridges and valleys. Certain of the shingles being convex as shown at 24. The 35 other shingles are concave as shown at 25.

Referring to Figure 23, tile shingles 24' of the concaved and convexed types are provided on their inner faces with recesses and a filler 25' is placed between the same and the slab or body. 40 The material of the filler is of a fibrous nature mixed with a binder so as to adhere to the shingles and slab. The material entering the recesses of the shingles is clearly shown in the drawings.

Referring to Figures 24 to 26 inclusive a facing 45 26 is provided and secured to the body or slab 27 as heretofore described and represents clapboarding. The facing 26 being constructed of cement or similar material.

Referring to Figures 27 to 29 inclusive, the 50 facing 28 is secured to a slab or body 29 in the heretofore described method and is constructed of cement which is grooved and its outer face highly polished to represent tiling for interior construction.

Referring to Figures 30 and 31, the body 30 has a facing 31 secured thereto in the method heretofore described and is constructed from plastic or similar material, the surface of which may have a roughened appearance or a white 60 coating so that when assembled in wall construction will have the appearance of plaster walls for interior construction.

From the foregoing description taken in connection with the accompanying drawings, it will 65 be noted that a device has been provided which may be cheaply manufactured and is heat and cold resisting, also fire resisting and durable so as to be capable of withstanding severe strains or stresses and when assembled in wall construction will be waterproof as well as vermin-proof.

While I have shown and described the preferred embodiment of my invention, it will be understood that minor changes in construction, combination and arrangement of parts may be made.

without departing from the spirit and scope of my invention, as claimed.

Having thus described my invention, what I claim is:

- 5 1. An article of manufacture comprising, a slab composed of shredded fibrous material treated to render the same fireproof and having a facing composed of spaced elements of refractory material and a coating of magnesium chloride covered by a coating of cement, said coatings acting to secure said refractory facing elements and slab together.
- 10 2. An article of manufacture comprising, a slab composed of shredded grass treated to render the same fireproof, and having a facing composed of spaced elements of refractory material, and a coating of magnesium chloride covered by a coating of cement, said coatings acting to secure said refractory facing elements, and slab together.
- 15 3. An article of manufacture comprising, a slab composed of shredded weeds treated to render the same fireproof, and having a facing composed of spaced elements of refractory material and a coating of magnesium chloride covered by a coating of cement, said coatings acting to secure said refractory facing elements and slab together.
- 20 4. An article of manufacture comprising, a slab composed of shredded fibrous material treated to render the same fireproof, and having a facing composed of faced elements of refractory mate-
- rial, and a coating of magnesium chloride covered by a coating of cement, said coatings acting to secure said refractory facing elements and slab together, two opposite sides of the article being oppositely rabbeted, and two other opposite sides being recessed to sealingly complementally fit corresponding recessed sides of another article to form a sealed wall, or facing for a wall. 5
- 25 5. An article of manufacture comprising, a slab of refractory material, a facing for the slab composed of spaced elements of refractory material cemented by means including magnesium chloride, two opposite sides of the article being oppositely rabbeted, and two other opposite sides being recessed to sealingly complementally fit corresponding recessed sides of another article, to form a sealed wall, or facing for a wall. 10
- 30 6. An article of manufacture comprising, a slab of refractory material, a facing for the slab composed of spaced elements of refractory material and a coating of magnesium chloride covered by a coating of cement, said coatings acting to secure said refractory facing and refractory slab together, two opposite sides of the article being oppositely rabbeted, and two other opposite sides being recessed to sealingly complementally fit corresponding recessed sides of another article, to form a sealed wall or facing for a wall. 15
- 35 25
